FLEXIBLE POCKET RECEPACLE

Douglas J. Broughton, Springfield, Mass., assignor
to Buxton, Incorporated, Springfield, Mass., a
corporation of Massachusetts

Application December 10, 1945, Serial No. 633,947

4 Claims. (Cl. 150—38)

1

This invention relates to an improved construction for flexible pocket receptacles such as billfolds.

This application is a continuation in part of my copending application Serial No. 598,835 filed June 11, 1945, now Patent No. 2,489,364 issued November 29, 1949, in that the present invention involves a specific adaptation of certain broad features disclosed in said copending application.

In the manufacture of billfolds it is desirable to avoid the use of stitching, and where stitching cannot be entirely avoided to keep it at a minimum and so construct the billfold that the stitching is subjected to a minimum amount of strain. Where it is desired to combine different types or colors of leather in a billfold the various parts must be secured together and this in the past has frequently required an undesirable amount of stitching and the location of stitches in undesirable positions in the billfold structure. Furthermore an increased demand by billfold users for the incorporation of a plurality of hinged pass-case holders in the billfold with means to confine such holders, as well as means for holding the billfold closed, that is folded, has further complicated the problems of providing multi-colored billfolds while at the same time avoiding undesirable quantities and locations of stitches.

The principal object of the present invention is to overcome the difficulties and problems mentioned and to provide a construction applicable to a relatively wide variety of billfold arrangements in which two or more colors or types of leather may be combined together with desired closure members, all with a minimum of stitching and conforming to acceptable practice with respect to the location of the stitching.

Other and more specific objects and advantages will be made apparent in the following specification and claims.

Fig. 1 is a detail view of the rear wall member and end closure flaps in unfolded condition;

Fig. 2 is a detail view of the panel and flap member, which is to be associated with the left hand end section of the rear wall member of Fig. 1, in unfolded condition;

Fig. 3 is a similar view of the panel and flap member to be associated with the right hand end section of the rear wall member of Fig. 1;

Fig. 4 is a detail view of the intermediate wall member;

Fig. 5 is a detail view of the pass-card supporting member;

Fig. 6 is a fragmentary view, parts being broken away showing the assembly of the parts forming

the left end section of the billfold as viewed in Fig. 1;

Fig. 7 is a similar view of the right end section;

Fig. 8 is a detail view showing the manner of connecting the pass card holders to their supporting member;

Fig. 9 is a view of the completed billfold in open position;

Fig. 10 is a view of one step in the assembly of the parts shown in Fig. 7;

Fig. 11 is a fragmentary view of an alternative form of rear wall member;

Fig. 12 is a detail view of a panel and flap member similar to that shown in Fig. 3 but modified for use with the rear wall member of Fig. 11;

Fig. 13 is a view similar to Fig. 7 but showing the assembly formed from parts modified as in Figs. 11 and 12;

Figs. 14 and 15 are view similar to Figs. 11 and 12 but showing a further modification of the parts; and

Fig. 16 is a view similar to Fig. 13 but showing the assembly formed from the modified parts shown in Figs. 14 and 15.

25 Referring to the drawings Figs. 1 to 9 show a billfold, embodying my invention, in which a pass-case and closure means as well as billfold closure means are provided. The billfold is made up of the five pieces of leather, or equivalent material, shown respectively in Figs. 1 to 5 inclusive. These pieces comprise a rear wall member 1 having end closure flaps 2 and 3 extending from opposite ends thereof as shown in Fig. 1. In Fig. 2 is shown a panel member 4 provided with a flap member 5 which, when folded as later described, becomes a wall member of one end section of the front wall assembly. Each of the members 4 and 5 is provided with an extension or tongue in the form indicated at 6 and 7 respectively. In Fig. 3 is shown a second panel member 9 provided with a flap 10 which when folded as later described becomes a wall member of the other end section of the front wall assembly. Each of the members 9 and 10 is provided with an extending tongue indicated at 11 and 12 respectively. The lower edge of member 9 is formed with a stitching tab 13. In Fig. 4 is shown an intermediate wall member 14 of conventional form, having end projections 15.

30 In one manner of assembling the elements so far described, the upper edge portion 16 of the rear wall member 1 is folded over and cemented thereon to form a finished edge in accordance with usual practice. It will be assumed that as 35 viewed in Fig. 1 the flesher side of the leather is

uppermost and that in Figs. 2, 3 and 4 grain side is uppermost. The panel member 4 is superimposed on the left end of member 14 as viewed in Fig. 4 and flap 5 is folded over the upper edge of member 14 with the adjacent projection 15 extending rearwardly through a slot 17 formed in flap 5. Similarly member 9 is superposed on the right end of member 14, the flap 10 being folded over the upper edge thereof with the adjacent projection 15 on member 14 extending rearwardly through slot 18 formed in flap 10. The described folding operations position tongues 6 and 7 in coinciding back to back relation. In such position they are inserted outwardly through a slot 19 formed in end member 2 adjacent its line of fold, end member 2 being folded over into superposed position on member 4 as shown in Fig. 6. Similarly the superposed tongues 11 and 12 are inserted through slot 20 formed in member 3 and the latter folded onto member 9 as shown in Fig. 7.

The pass-card supporting member shown separately in Fig. 5 comprises an attaching portion 21, provided with a stitching tab 22, and a cover forming portion 23, the portion intermediate portions 21 and 23 being folded along lines 24 as shown in Fig. 8 to provide means to which a plurality of card holders 25 may be connected as by a conventional spiral wire or plastic binding member 26. Member 21 is inserted between members 4 and 14 as shown in Fig. 6 with the stitching tab 22 aligned with tabs 8 and 13 along the bottom edge of the rear wall 1. A single line of stitching 27 along the bottom edge of each end section below the bottom edge member 14 serves to hold the parts together. The tongues 6 and 7 are cemented together outwardly of the billfold, as are tongues 11 and 12. The pass case cover member 23 is shown provided with a strap 28 beneath which two ply tongue 6—7 releasably engages to hold the pass case closed. The two ply tongue 11—12 is provided with one member 29 of a snap fastener, the other member 30 of the fastener being secured to the rear wall 1 (Fig. 1), providing means for releasably holding the billfold closed.

The assembly sequence above described is not essential. For example if desired the end section panel and flap members may be inverted as shown in Fig. 10 and the tongue extension 12 carried by the flap 10 inserted through slot 20. The base of tongue 12 may then be stitched, as a flat stitching operation, to the rear wall, as at 31, to close the opening between the tongue and the rear wall thus preventing any tendency of this opening to gap when the billfold is closed. Member 14 is then superposed on member 10 with the adjacent projection 15 extending through slot 18, flap 9 folded down on member 14, tongue 11 inserted through slot 20, flap 3 folded over on member 9, bringing the parts into position to be stitched as previously described. It will be understood that the other end may be similarly constructed. In the form shown in Figs. 11, 12 and 13 the rear wall 32 is provided with a bottom closing flap 33 extending from the lower edge thereof. End section panel member 34 is provided with a flap 35, the members 34 and 35 being formed with extensions 36 and 37 respectively, these members being substantially similar to the corresponding members of the form previously described, except that the bottom edge of member 34 is not cut away to form a stitching tab. The flap member 35 is folded over an intermediate wall member 38 (Fig. 13) identical with mem-

ber 14 previously described and having projections not shown which engage in the slot 39 formed in flap 35. The so assembled parts are superimposed on rear wall 32 with the superposed tongues 36 and 37 extending from the end of the billfold and bottom flap 33 is folded up over member 34 as shown in Fig. 13, the outer end edges of members 34 and 35 coinciding with the adjacent end edge of rear wall 32. A single line of stitching 40 at each end of the billfold serves to hold all the parts in position. Tongues 36 and 37 are cemented together as previously described.

A modified arrangement of the form just described is shown in Figs. 14, 15 and 16 in which the rear wall 32 is provided with an integral extension tongue 41, in a position to underlie and coincide with tongues 37 and 36 when the parts are assembled as previously described, providing a three ply tongue. Preferably tongue 37 is shortened as shown at 42 in Figs. 15 and 16. Shortened tongue 42 is at least of sufficient length to be included in and held by the line of stitching 40, and may extend a short distance outwardly of the end of the billfold between tongues 41 and 36, the latter being cemented to tongue 42 and to each other.

I claim:

1. In a billfold of the type having end sections foldable one on the other about a transverse line of fold and having a rear wall extending throughout the length of the billfold, an end section construction comprising a front wall member extending from an edge of the rear wall and folded onto the flesher side of the rear wall, a line of stitching connecting the adjacent free edges of the rear wall and said front wall member to form a pocket open at the top and along the side adjacent said transverse line of fold, a panel member formed as a separate piece and positioned in said pocket, at least a portion of one edge of said panel member being included in said line of stitching to hold the panel member in position, a flap extending from the upper edge of the panel member and folded downwardly into said pocket, tongues formed integral with said panel member and said flap and extending in superposed relation outwardly through an enabling means in the closed side of the pocket at the end of the billfold.

2. In a billfold of the type having end sections foldable one on the other about a transverse line of fold and having a rear wall extending throughout the length of the billfold, an end section construction comprising a front wall member extending from the end edge of the rear wall and folded onto the flesher side of the rear wall with a slot in its line of fold, a line of stitching connecting the lower edges of the rear wall and said front wall member to form a pocket, a panel member formed as a separate piece and positioned in said pocket, at least a portion of the lower edge of said panel member being included in said line of stitching, a flap extending from the upper edge of the panel member and folded downwardly into said pocket at the rear of the panel member, tongues formed integral with said panel member and said flap and extending in superposed relation outwardly through said slot and means connecting said tongues together outwardly of said slot.

3. In a billfold of the type having end sections foldable one on the other about a transverse line of fold and having a rear wall extending throughout the length of the billfold, an end section construction comprising a front wall member extend-

ing from the bottom edge of the rear wall and folded onto the flesher side of the rear wall, a line of stitching connecting the end edges of the rear wall and said front wall member to form a pocket, a panel member formed as a separate piece and positioned in said pocket, at least a portion of the end edge of said panel member being included in said line of stitching, a flap extending from the upper edge of the panel member and folded downwardly into said pocket at the rear of the panel member, tongues formed integral with said panel member and said flap and extending outwardly from the end of the pocket, in superposed relation, through said line of stitching.

4. In a billfold of the type having end sections foldable one on the other about a transverse line of fold and having a rear wall extending throughout the length of the billfold, an end section construction comprising a front wall member extending from the bottom edge of the rear wall and folded onto the flesher side of the rear wall, a line of stitching connecting the end edges of the rear wall and said front wall member to form a pocket, a panel member formed as a separate piece and positioned in said pocket, at least a portion of the end edge of said panel member being included in said line of stitching, a flap extending from the upper edge of the panel member and folded down-

wardly into said pocket at the rear of the panel member, tongues formed integral with said panel member and said flap and extending outwardly from the end of the pocket, in superposed relation, through said line of stitching, the rear wall having an integral tongue extending from its end rearwardly of and coinciding with the tongue extending from said panel member, the tongue extending from the flap being shorter than the tongues carried by the rear wall and panel member but at least of a length to be included in said line of stitching, the last mentioned tongues being connected together outwardly of said short tongue.
